UNITED STATES PATENT OFFICE.

JOSEPH W. HOPKINS, OF BROOKLYN, NEW YORK, ASSIGNOR TO HIMSELF
AND JAMES CLAYTON, OF SAME PLACE.

IMPROVEMENT IN VALVES FOR STEAM-ENGINES.

Specification forming part of Letters Patent No. 10,445, dated October 27, 1863.

To all whom it may concern:

Be it known that I, JOSEPH W. HOPKINS, of Brooklyn, in the county of Kings and State of New York, have invented a new and Improved Steam-Valve; and I do hereby declare that the following is a full, clear, and exact description of the same, reference being had to the accompanying drawings, forming a part of this specification, in which—

Figure 1 represents a plan or top view of my invention. Fig. 2 is a longitudinal vertical section of the same, the line *x x*, Fig. 1, indicating the plan of section.

Similar letters of reference indicate corresponding parts in both figures.

This invention relates to an improvement in that class of steam-valves in which the motion of the valve is partially effected by the action of the steam, so that the ports are wide open when the piston has arrived at either end of the cylinder, and the full force of the steam acts on the piston throughout its whole stroke.

My improvement will be readily understood from the drawings and the following explanation.

B represents an oscillating hollow disk, the lower part of which, at A, is made into the form of a convex slide-valve, which moves in a corresponding concave seat within the steam-chest C, as shown in Fig. 2. The disk B is bored out to fit to the round body of the valve D, which is rigidly attached to the spindle E', and to which an oscillating motion is imparted by cams or other suitable means from the piston-rod.

The valve D is provided with an abutment or wing, *a*, which fits into a segmental cavity, *b*, in the disk B, and said cavity communicates with the interior of the steam-chest through the port *c*. The valve D, on being oscillated in the cavity of the disk B, alternately opens and closes the exhaust-channels *d d'*, which extend on either side of the abutment *a* from

the center of the disk to the cavity in the slide-valve A, as clearly shown in Fig. 2 of the drawings.

The motion of the slide-valve is limited by stops *e e'* on either end of its seat. If the slide-valve is not rigidly connected with the disk, the steam from the cavity *b* may be made to exhaust through channels passing out parallel to the spindle E' through the sides of the steam-chest.

The valve-chest communicates with the interior of the steam-cylinder through ports F F', and the steam from the cylinder exhausts through the port E.

The operation is as follows: In the position shown in Fig. 2 the cylinder takes steam through the port F, and the piston moves in the direction of arrow 1. At the proper moment, and before the piston has completed its stroke, the valve D is turned in the direction of arrow 2, against the steam which fills the cavity *b*, having free access to the same through the port *c*. As soon as the abutment *b* passes the port *c*, the channel *d* is opened, allowing the steam before the abutment to escape, and the space behind the abutment fills with steam and causes the disk to rotate suddenly in the direction of arrow 3.

The port F' is thereby thrown wide open and the port F brought in communication with the exhaust-port E, thus giving a full head of steam to the piston at the beginning of its return-stroke.

What I claim as new, and desire to secure by Letters Patent, is—

The combination, with the steam-chest C and the valve D, of the independent oscillating hollow disk and slide-valve B A, all constructed and operating together in the manner herein shown and described.

JOSEPH W. HOPKINS.
